UNITED STATES PATENT OFFICE

VINCENZO SCIAMANNA, OF BRADDOCK, PENNSYLVANIA, ASSIGNOR OF ONE-HALF TO
RANIERO STURBO, OF BRADDOCK, PENNSYLVANIA

WALL-FACING TILE

Application filed March 31, 1928. Serial No. 266,356.

This invention relates to wall facing tiles and more particularly to a wall for use in the formation of finished wall faces which may be employed as a substitute for finished brick.

An important object of the invention is to provide a device of this character which may be readily and rapidly installed and which is firmly anchored to the wall by supports which it carries and without the necessity of other supports.

A still further object of the invention is to produce a device of this character which may be readily and cheaply manufactured, which will be durable and efficient in service and a general improvement in the art.

These and other objects I attain by the construction shown in the accompanying drawings, wherein for the purpose of illustration is shown a preferred embodiment of my invention and wherein:

Figure 1 is a vertical sectional view showing a wall faced with tile constructed in accordance with my invention;

Figure 2 is a front elevation thereof.

Figure 3 is a plan view of a single tile.

Referring now more particularly to the drawings, the tile comprises a substantially rectangular body, generally designated at 10, and having a smooth outer face 11. The side edges of this body are preferably constructed, as at 12, for tongue and groove engagement with adjacent tiles. The inner face of the tile is corrugated, so that it will be very firmly gripped by mortar placed between the wall face and the tile facing. The corrugation of its inner face provides the tile at said face thereof with outer and intermediate vertical ribs 13, which extend from the lower to the upper edge of the body of the tile, as clearly shown in Figures 1 and 3.

In the process of construction, the body of the tile has embedded therein flexible corrugated strips 14 which may either be bodily corrugated or have their side edges corrugated as illustrated.

A tile of this character is intended for use in connection with brick walls and the tile laid as the wall rises. In applying the tile, the strips 14, which project from the body at the rear face thereof and adjacent its top, are bent at right angles to the body and are extended between adjacent courses of bricks 15 of the wall, so that they are embedded in the mortar 16 between these courses. Mortar is placed between the front face of the brick wall and the rear face of the tile, as indicated at 17, and a small amount of mortar may, if so desired, be placed between the edge faces of adjacent tiles. The vertical members of the anchoring strips 14 are embedded in the intermediate ribs 13 of the tile, and the horizontal members of the anchoring strips extend from the ribs at points close to the upper ends of the latter, as clearly shown in Figures 1 and 2.

It will be obvious that a tile of this character may be very readily and rapidly installed and will eliminate the necessity for face brick so that the cost of construction of the building will be materially reduced.

It will also be obvious that the construction hereinbefore set forth is capable of a certain range of change and modification without materially departing from the spirit of the invention and I accordingly do not limit myself to such specific structure except as hereinafter claimed.

I claim:

1. A wall facing tile comprising a body provided at its inner face with vertical ribs, and angular anchoring strips having vertical members embedded in the ribs and having corrugated horizontal members extending from the ribs at points close to the upper ends of the latter.

2. A wall facing tile comprising a body angular in contour and provided at its inner face with outer and intermediate vertical ribs, the ribs extending from the lower to the upper edge of the body, the body being pro-

vided in certain of its edges with grooves and at its other edges with tongues, and anchoring strips having vertical members embedded in the intermediate ribs and having horizontal members provided with corrugated edges and extending from the intermediate ribs at points close to the upper ends of the latter.

In testimony whereof I hereunto affix my signature.
